FERDINAND SATTERSTROM, OF FARIBAULT, MINNESOTA, ASSIGNOR TO THE SPIRAL CUTTER COMPANY, OF FARIBAULT, MINNESOTA, A CORPORATION OF MINNESOTA

APPARATUS FOR GRINDING TOOLS

Application filed February 23, 1927. Serial No. 170,212.

This invention relates to new and useful improvements in grinding apparatus, and more particularly to such apparatus adapted for use to grind or sharpen the blades of spiral cutter-heads.

An object of the invention is to provide means in connection with such an apparatus for relatively rotating the work or cutter-head with respect to the grinder-wheel so that the cutting edges of the blades thereof will be accurately ground to the same angle, thus insuring a smooth cut of the cutter-head when in operation.

A further object of the invention is to provide an apparatus for grinding the blades of cutter-heads of the type shown in Patent #1,432,792, granted to F. Schimmel, said apparatus having means adapted to engage the radial wall of one of the guide channels therein to accurately guide and rotate the cutter-head with respect to the grinder-wheel, as the cutter-head is longitudinally moved back and forth with one of its blades in grinding engagement with the grinder wheel, thus insuring that each blade of a cutter-head will be ground to exactly the same cutting angle.

A further object is to provide a guide for the cutter-head having an adjustable support whereby it may readily and quickly be adjusted to guide either a right or a left hand spiral cutter.

Features of the invention reside in the general mounting of the guide means for guiding the cutter-head with respect to the periphery of the grinder-wheel; the adjustability of such guide means; the particular mounting of the grinder-wheel which is such that the wheel may readily and quickly be adjusted to suit various sizes of cutter heads, and by the adjustment of which the cutting angles of the blades may also be varied, as desired, and, in the general construction of the grinder, as a whole, which, it will be seen, is very simple and comprises few moving parts.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the accompanying drawings forming part of this specification:

Figure 1 is a vertical sectional view on the line 1—1 of Figure 2;

Figure 2 is a plan view of Figure 1;

Figure 3 is a front elevation of Figure 2;

Figure 4 is an enlarged detailed sectional view showing the means for guiding the cutter-head with respect to the grinder-wheel;

Figure 5 is a detailed sectional view on the line 5—5 of Figure 4;

Figure 6 is an enlarged detailed sectional view on the line 6—6 of Figure 1, showing the means provided for changing the angle of the guide-head whereby it may be used to guide either a right or a left-hand cutter-head;

Figure 7 is a detailed sectional view on the line 7—7 of Figure 6;

Figure 8 is a detailed sectional view of the lower portion of the guide-head, showing the yieldably mounted blade provided therein;

Figure 9 is a detailed sectional view showing the supporting means for the grinder-wheel;

Figure 10 is a view showing a modified form of guide;

Figure 11 is a detailed sectional view on the line 11—11 of Figure 10;

Figure 12 is a view showing another modified form of guide;

Figure 13 is a plan view of a grinder adapted for use to grind comparatively long cutter-heads which cannot be longitudinally moved upon their supporting spindles; and

Figure 14 is a vertical sectional view on the line 14—14 of Figure 13.

The novel grinding apparatus featured in this invention comprises a base member 21 having bearings 22 and 23 mounted thereon for supporting a spindle or shaft 24, upon which the cutter-head or work 25 is adapted to be slidably and rotatably mounted. An

upright bracket 26 is mounted upon a slide 27 mounted in suitable run-ways or guides 28, provided upon the base member 21. A grinding wheel 29 is adjustable mounted upon the bracket 26.

5 The supporting means for the grinding wheel 29 consists of a stud 31 having an enlarged portion 32 against which a ball-bearing 33 is seated. A similar ball-bearing 34 is mounted upon the stud 31 adjacent the outer end thereof, and is arranged thereon substantially in alignment with a pulley 35, terminally secured to a flanged sleeve 36 by such means as threads 37. The grooved pulley 35 has a central portion 38 which preferably is squared so that the pulley may be tightened against the grinder-wheel 29 which, it will be noted by reference to Figure 9, is clamped between the flange 39 of the sleeve 36 and the inner face of the grooved pulley 35. The inner ball-bearing 33 is arranged in alignment with the grinder-wheel 29 as shown. Suitable packings 41 are provided adjacent each ball-bearing to prevent oil leakage therefrom. The stud 31 is also provided with a flange 42 and next to this flange is a threaded portion 43 adapted to receive a wheel-guard 44, which overhangs the grinding-wheel 29 and partially conceals it, as shown in Figure 1. The stud 31 has a threaded extension 45 adapted to pass through an arcuately formed slot or aperture 46 provided in a web 47, preferably integrally formed with the bracket 26, as also shown in Figure 1. A cap screw 48 passes through an apertured boss 49 on the bracket 26 and has its inner threaded portion received in a threaded socket provided in the wheel-guard 44, as shown in Figure 2. This cap screw 48 provides a pivotal connection between the wheel-guard and the bracket 26. A wing nut 51 is terminally mounted upon the threaded extension 45 of the stud 31, and provides means for securing the wheel-guard, and therefore the grinding-wheel in adjusted positions. This adjustment provides means for moving the grinding-wheel to and from the axis of the cutter-head 25. (See Figure 1.)

10 A motor 52 has a bracket 53 secured thereto, which in turn, is adjustably secured to the slide 27 by means of a cap screw 54. The bracket 53 is slotted as shown in Figure 2, so that the motor may be relatively moved, with respect to the grinding-wheel 29 for the purpose of adjusting the tension of the belt 55, operatively connecting the motor with the grinding-wheel 29. An adjusting screw 56 has one end received in threaded engagement with the slide 27 and has its outer portion 15 rotatably mounted in a bracket 57, suitably secured to the base member 21, as shown in Figures 1 and 2. Collars 58 and 59 are secured to the adjusting screw 56 to prevent longitudinal movement thereof, when the screw is rotated to relatively adjust the posi-

tion of the slide 27 upon the base member 21. A suitable hand wheel 61 is terminally secured to the adjusting screw 56 to provide means for rotating the latter. From the foregoing, it will be noted that the slide 27, carrying the motor 52 and the bracket 26 upon which the grinding-wheel 29 is mounted, may be relatively adjusted with respect to the cutter-head 25; that is, when the adjusting screw is rotated in one direction, the grinding-wheel will be moved backwardly away from the cutter-head and, when it is rotated in the opposite direction, it will be moved towards the cutter-head. By thus adjustably mounting the bracket 26 upon the base member 21 and by the adjustable mounting of the grinding-wheel upon the bracket 26, the grinding-wheel may be quickly adjusted to the desired position required for grinding the blades 62 of a given cutter-head.

15 An important feature of this invention resides in the novel means provided for relatively rotating the cutter-head upon the spindle 24, when the cutter-head is longitudinally moved back and forth upon the spindle, during the blade-sharpening or grinding operation. This apparatus is particularly designed for use to grind the blades of spiral cutter-heads such as the type set forth in the above mentioned patent, and also as shown in Figure 5 of the present application. It will readily be understood that to accurately grind the blades of such a cutter-head, means must be provided for accurately guiding the cutting edge of the blade with respect to the periphery of the grinding-wheel 29 so that a true cutting edge may be obtained, and also whereby the face angle of each blade will be accurately ground with respect to one another and with respect to the axis of the 20 cutter-head. As a result of the spiral arrangement of the blades in the periphery of the cutter-head, it is necessary that the cutter-head be relatively rotated upon the spindle 24, during the reciprocal movement of the cutter-head 25 when in grinding engagement with the grinder wheel 29.

25 The means provided for thus guiding and rotating the cutter-head as it is moved backwardly and forwardly upon the spindle 24 with one of its blades in grinding engagement with the periphery of the wheel 29, consists of a guide-head 63 having a straight edge portion 64 provided thereon adapted to engage the walls 65 of the clearance channels or grooves 66, shown in Figures 1 and 4. These grooves are common in the construction of the cutter-head and have the dual function of providing clearance for the chips removed from the work and also as a means 30 adapted to co-operate with other means for guiding the cutter-head with respect to the grinder-wheel 29.

35 The guide-head 63 is preferably shaped as shown in Figure 4, and has a spring-actuated

blade 68 mounted therein adapted to engage the adjacent face of the cutter blade 62, to constantly retain the wall 65 of the clearance groove 66 in guiding engagement with the straight edge or face 64 of the guide-head. By means of the spring-actuated blade 68, the wall 65 will always be held in contact with the straight edge 64 so that the relative position of the cutting edge of the blade 62 will not vary with respect to the periphery of the 10 grinding-wheel 29 for a given setting of the various parts. The blades 62 of the cutter-head are adjustably secured to the head by means of wedge-shaped clamping blocks 69 and cap screws 71, as shown in Figure 4.

The guide-head 63 has a shank 72 received in a socket 73 provided in a supporting member 74, having a cylindrical extension 75 which is terminally threaded and received in an arm or link 76, as shown in Figure 6. A 20 clamping member 77 is bored to receive the extension 75 and has one end adapted to engage the arm 76 and its other end adapted to engage the shank 72 of the guide-head 63 as shown in Figures 6 and 7. By thus mounting the clamping member 77 upon the extension 75 of the supporting member 74, it will readily be noted that when the nut 78 is rotated upon the extension 75, that the 25 shank 72 will be securely clamped by the supporting member 74 and the clamping member 77. The above clamping means also permits the shank 72, and therefore the guide-head 63, to be vertically adjusted therein with respect to the cutter-head. The arm 76, to which the guide-head 63 is adjustably secured, is provided with an elongated opening or slot 79 adapted to receive one end of a 30 clamping screw 81, terminally mounted in a bracket 82 secured to the base member 21, as shown in Figures 2 and 3. The adjustable mounting of the arm 76 upon the bracket 82 provides means for further adjusting the 35 guide-head with respect to the cutter. Therefore, by means of the slot 79 in connection with the adjustable mounting of the guide-head 63 upon the arm 76, the guide-head may be universally adjusted with respect to the 40 cutter-head so that it may be accommodated to practically all sizes and shapes of cutter-heads within a reasonable limit, of course.

Another feature of the guide-head supporting means is shown in Figure 6 and consists in arranging the socket 73 at an angle in the supporting member 74 so that the shank 72 of the guide-head may be arranged at a slight incline with respect to the axis of the stud 75. This is essential in order that the straight edge or face 64 of the guide-head will be arranged substantially parallel to the cutting-edge of the blade 62 of the cutter-head, during the grinding operation. As a result of the spiral mounting of the blade 62 in the cutter-head, the cutting edges thereof are not parallel to the axis of the cutter-

head or the supporting spindle 24. The axis of the socket 73 is therefore arranged at an angle with respect to the axis of the extension 75 of the support, so as to compensate for the spiral mounting of the blades 62 in 70 the cutter-head. The supporting means for the cutter-head is so arranged that it may be used for grinding either right or left hand spiral cutters. The full line position shown in Figure 6 illustrates the guide-head as arranged when used for guiding right hand spiral cutters, and the dotted line position indicates the position assumed when used to guide left hand spiral cutters. The two above described positions are obtained by merely 75 reversing the position of the guide-head supporting means. That is, when it is desired to adjust the guide-head from the full to the dotted line position shown in Figure 6, the shank 72 will be withdrawn from the socket 73 and the clamping means, including the members 74 and 77, will be rotated a half revolution in the arm 76, after which the shank 72 will be inserted into the socket 73 of the guide-head 74. The guide-head will then 80 assume the dotted line position shown in Figure 6. The opposite end portions 83 and 84 of the guide-head are preferably rounded, as shown in Figures 5 and 6, so as to readily enter the channels or grooves 66, during the 85 reciprocal movement of the cutter-head upon the spindle 24 when the blades are being ground or sharpened.

Figures 10 and 11 illustrate a modified form of guide-head wherein a flattened member 85 is secured to the shank 72 and has a flexible or yieldable member 86 secured thereto adapted to engage one side of a tongue or rib 87 provided upon the cutter-head 88. This form of guide-head functions in a manner similar to that shown and described in the previous figures, but instead of the guide-head having means engageable with the cutter-head blade 62 to retain the guide wall 89 in constant engagement with the guide-head, the flexible member 86 is provided which, it will be noted by reference to Figures 10 and 11, is adapted to engage the rear wall of the longitudinal guide rib 87, provided upon this form of cutter-head. The opposite end portions of the cutter-head 85 are rounded as shown at 91, and the end portions of the flexible member 86 are outwardly turned as indicated at 92, so that the rib 87 will readily enter between the guide-head 85 and member 86, when 105 moving the cutter-head back and forth upon the spindle 24 during the grinding operation.

Figure 12 shows another modification of the guide-head wherein a flexible member 93 is secured to the guide-head 94 on the side adjacent to the cutter-head blade 62. In the form here shown, the cutter-head is provided with a groove 95 having a guide wall 96 adapted to be engaged by the guide 94 as 110 115 120 125 130

shown. The spring member 93 merely functions to retain the wall 96 in constant engagement with the guide head during the grinding operation.

5 Figures 13 and 14 illustrate a grinding apparatus adapted for use to grind the blades of relatively long cutter-heads which cannot readily be removed from their supporting spindles or longitudinally moved thereon. In 10 the form here shown, the grinding apparatus is moved with respect to the cutter-head. A guide rail 97 is arranged over the cutter-head 98 and is supported by brackets 99, mounted upon the pedestals or bearings 101 supporting the spindle or shaft 102 of the cutter head. A carriage 103 is movably mounted upon the rail 97, and to this carriage the grinder wheel 104 is mounted by means of a bracket 105 adjustably secured to a slide 106 vertically 15 movable in suitable guides 107 provided in the carriage 103. A motor 108 is also mounted upon the slide 106 and is adjustable thereon to vary the tension of the drive belt 109 operatively connecting the motor with the 20 grinding wheel 104. An adjusting screw 111 is mounted in a lug 112 provided at the upper portion of the slide 106 and has a hand wheel 113 whereby the slide 106 may be vertically adjusted in the carriage 103 to relatively adjust 25 the position of the grinding wheel 104 with respect to the blades 114 of the cutter-head 98. A guide head 115 is adjustably secured to a depending member 116 secured to the bracket 105 by suitable bolts 117. A cap 30 screw 118 is provided for securing the guide head to a depending member 116, shown in Figure 14. The slide 106 is secured to the carriage 103 by means of a clamping bar 119 as shown in Figure 13.

40 In the operation of the grinding apparatus shown in Figures 13 and 14, the cutter head 98 is not removed from its drive spindle 102, but the spindle 102 is released from its driving mechanism or permitted to freely rotate, 45 so that when the carriage 103 is moved back and forth upon the rail 97, the guide head 115 will rotate the cutter head 98 as the grinding wheel is moved back and forth, thereby 50 accurately grinding or sharpening the cutting edges of the blades in a manner similar to that shown and described with reference to Figures 1, 2 and 3.

From the foregoing therefore, it will readily be seen that the novel grinding apparatus 55 featured in this invention is adapted for use to grind practically all types of spiral cutters. It may also be utilized for grinding cutters wherein the blades are arranged parallel to the axis of the cutter-head. The mounting 60 of the grinding wheel is such that the cutting edges of the blades may be ground at practically any desired angle. Also, by means of the yieldable means provided in the guide head 63, the blade will always be retained in 65 constant uniform engagement with the pe-

riphery of the grinding wheel for each setting, thereby insuring that all of the blades of a given cutter head will be uniformly and accurately ground with respect to the axis thereof.

70 I claim as my invention:

1. In an apparatus for grinding cutter heads, each having a plurality of cutter blades and a longitudinally extending guide tongue or rib adjacent to each blade, the combination of a support for the cutter head, a grinding wheel, a cutter guide member adapted to engage a wall of one of said guide tongues, and a yieldable element supported on said guide member and adapted to engage the opposite wall of said guide tongue and hold said guide member in contact with said tongue to prevent back lash, and whereby each cutter blade may be accurately ground.

75 2. In an apparatus for grinding cutters, each having a plurality of cutter blades and a longitudinally extending guide tongue or rib adjacent to each blade and spaced therefrom, the combination of a support for the cutter, a grinding wheel, a guide member adapted to engage one wall of the guide tongue adjacent to the blade being ground, and yieldable means secured to said guide member and engaging the opposite wall of 80 said guide tongue and co-operating with said guide member to retain the cutting edge of said blade in true grinding relation with respect to the periphery of the grinding wheel.

85 3. In an apparatus for grinding cutters, each having a plurality of cutter blades and a longitudinally extending guide tongue or rib in the periphery of said cutter adjacent to each cutter blade and spaced therefrom, the combination of a support for the cutter, 90 a grinding wheel, an adjustable support for said grinding wheel, an adjustable guide member adapted to engage a radial wall of the guide tongue adjacent to the blade being ground, and a flexible member being secured to said guide member and engaging the opposed radial wall of said guide tongue and co-operating with said guide member to retain the cutting edge of the blade being 95 ground, in true grinding relation with respect to the periphery of the grinding wheel.

100 4. In an apparatus for grinding cutters, each having a plurality of cutter blades and a longitudinally extending guide tongue or rib in the periphery of said cutter adjacent to each cutter blade and spaced therefrom, the combination of a support for the cutter, a 105 grinding wheel, an adjustable support for said grinding wheel, an adjustable guide member adapted to engage a radial wall of the guide tongue adjacent to the blade being ground, and a flexible member being secured to said guide member and engaging the opposed radial wall of said guide tongue and co-operating with said guide member to re- 110

tain the cutting edge of the blade being ground, in true grinding relation with respect to the periphery of the grinding wheel, said guide member being mounted for universal adjustment.

5. In an apparatus for grinding spiral cutter heads, each having a plurality of blades and a guide tongue or rib adjacent to each blade and spaced therefrom, the combination of a support adapted slidably to receive the cutter head, a grinding wheel, a cutter guide member adapted to engage a radial wall of one of said guide tongues, and a flexible member mounted upon said guide member and adapted to engage the opposite wall of said guide tongue and cooperating with said guide member to yieldably grip said guide tongue and to accurately guide and relatively rotate the cutter head, when said cutter head is axially moved upon said spindle whereby the spiral cutting edge of the blade being ground will be accurately held in grinding contact with the periphery of the grinding wheel.

6. In an apparatus for grinding spiral cutters, each comprising a plurality of cutter blades and having a longitudinally extending guide tongue or rib adjacent to each blade and spaced therefrom, the combination of a base member, a spindle mounted upon said base member and adapted to slidably support the cutter, a bracket on the base member, a grinding wheel adjustably mounted thereon, a guide member adjustably secured to said bracket and adapted to engage a radial wall of the guide tongue adjacent to the blade being ground, and a flexible member secured to said guide member and engageable with the opposite wall of said tongue and co-operable with said guide member to rotate the cutter, when the latter is longitudinally moved upon said support, to retain the cutting edge of the blade being ground in true grinding relation with the periphery of the grinding wheel.

7. In an apparatus for grinding spiral cutters, each having a plurality of blades and having a guide tongue adjacent to each cutter blade and spaced therefrom, the combination of a spindle having a relatively fixed support and being adapted slidably to support a cutter, a grinding wheel adjustable to and from said spindle, a bracket for supporting said grinding wheel, an arm adjustable on said bracket, and a guide means mounted on said arm and including cooperating members adapted to yieldably grip said guide tongue adjacent to the blade being ground, whereby said cutter will be relatively rotated upon said spindle, when longitudinally moved thereon, to accurately guide said cutter with respect to said grinding wheel.

8. In an apparatus for grinding spiral cutters, each having spiral cutter blades and having a spiral guide means adjacent to each

blade and spaced therefrom, the combination of a relatively fixed spindle adapted movably to support a cutter, a grinding wheel adjustable to and from said spindle, a bracket for supporting said grinding wheel, an arm 70 adjustable on said bracket, a guide member secured to said arm, and a flexible member secured to said guide member and cooperating therewith to engage one of said guide means and to rotate and guide said cutter with respect to said grinding wheel, when the cutter is longitudinally moved upon said spindle, said guide member retaining the cutting edge of the cutter blade being ground, in true grinding relation with respect to the 80 periphery of the grinding wheel, and said flexible member preventing backlash or play of the cutter with respect to the grinding wheel.

9. In an apparatus for grinding spiral cutters, each having a plurality of spiral blades and a longitudinally extending guide means adjacent to each blade, the combination of a spindle adapted slidably to support a cutter, a grinding wheel, a support for the grinding wheel, a clamping means adjustably secured to said support, a guide member adjustably mounted on said clamping means, a flexible member secured to said guide member and cooperating therewith to engage said 95 guide means and to guide and relatively rotate the cutter, when the latter is axially moved upon said spindle, said guide member being mounted for universal adjustment, whereby it may be positioned for guiding 100 either right or left hand cutters.

10. In an apparatus for grinding spiral cutters, each having a plurality of spiral cutter blades and a longitudinally extending guide means adjacent to each blade, the combination of a spindle adapted to slidably support the cutter head to be ground, a grinding wheel, a supporting bracket therefor, a clamping member adjustably mounted on said bracket, a socket in said clamping member, a guide member having a shank adapted to be adjustably secured in said socket, said guide member being adapted to engage the guide means in the periphery of said cutter and relatively rotate and guide the cutter on said spindle without back lash, when the cutter is axially moved thereon, and the socket in said clamping member being arranged at an angle with respect to a line drawn at right angles to the axis of said clamping member whereby, when said clamping member is in one position, said guide member may be positioned thereon to guide a right hand spiral cutter, and when said clamping member is inverted with respect to said supporting bracket, said guide member may be positioned to guide a left cutter.

11. In an apparatus for grinding spiral cutters, each having a plurality of spiral cutter blades and a longitudinally extending

guide means adjacent to each blade; the combination of a spindle adapted slidably to support a cutter, a grinding wheel, a supporting bracket therefor, a link adjustably secured to said bracket, a clamping member terminally secured to said link, a socket in said clamping member, a guide member having a shank adapted to be adjustably secured in said socket, said guide member being adapted to engage the guide means in the periphery of said cutter and to relatively rotate and guide said cutter without play, when the latter is axially moved upon said spindle, and the socket in said clamping member being arranged at an incline whereby, when said clamping member is in one position, said guide member will be positioned to guide a right hand spiral cutter, and when said clamping member is inverted with respect to said link, said guide member may be positioned to guide and rotate a left hand cutter.

In witness whereof, I have hereunto set my hand this 17 day of February, 1927.
